UNITED STATES PATENT OFFICE.

ROBERT MORGAN, OF ELLSWORTH, KANSAS, ASSIGNOR OF ONE-HALF TO
EMILE E. KOLOCHNEY, OF ELLSWORTH, KANSAS.

PIANO-PLAYER.

No. 856,794.

Specification of Letters Patent.

Patented June 11, 1907.

Application filed January 30, 1903. Serial No. 266,586.

To all whom it may concern:

Be it known that I, ROBERT MORGAN, a citizen of the United States, and a resident of Ellsworth, in the county of Ellsworth and State of Kansas, have invented a certain new and useful Improvement in Piano-Players, of which the following is a specification.

My invention is an improvement in piano players and consists in certain novel constructions and combinations of parts herein-after described and claimed.

Referring to the drawing forming a part hereof—Figure 1 is a perspective view of a piano provided with my improved player; Fig. 2 is a detail perspective view of the playing mechanism proper; Fig. 3 is a detail perspective view of a portion of the switch mechanism; Fig. 4 is a transverse section of the same; Fig. 5 is a perspective view of the current controlling mechanism with the cover in place; Fig. 6 is a detail of the insulating bar; Fig. 7 is a detail of the adjusting mechanism for the playing mechanism proper; Fig. 8 is a detail view of the frame adjusting mechanism. Fig. 9 is a top plan view of the same. Fig. 10 is a section on the line 10—10 of Fig. 8. Fig. 11 is a section on the line 11—11 of Fig. 8, and Fig. 12 is a detail perspective view of the yoke. Fig. 13 is a section on the line 13—13 of Fig. 4.

In the practical application of my invention, I provide a mechanism A for striking the keys, and a mechanism B for operating the striking mechanism.

The striking mechanism is arranged upon a frame comprising a base a' , having upturned ends a^2 , each of said ends being provided with a vertical slot a^3 , having upon one side thereof rack teeth a^4 . The outer faces 40 of the ends a^2 , are provided with vertical grooves a^5 for receiving ribs a^6 , upon a bracket a^7 , the said bracket being secured to the piano adjacent to the ends of the keyboard, by means of the clamps a^8 , and the set screws a^9 . The frame is slidable on the bracket, and is vertically adjusted with respect thereto by means of a pinion a^{10} secured to the end of a shaft a^{11} journaled in the bracket and adapted to engage the rack teeth a^4 of the slot a^3 . A handle a^{12} is loosely mounted upon the shaft outside of the bracket, and is provided with a grip a^{13} , connected by a rod a^{14} , with a catch a^{15} , normally maintained in contact with a ratchet wheel

a^{16} secured to the end of the shaft a^{10} between the handle and the bracket, by means of a spring a^{17} . A pawl a^{18} , pivoted to the bracket and engaging the ratchet wheel, is provided for retaining the same in its adjusted position. It is evident that when the handle is depressed, the pawl slips over the ratchet teeth, and that when the handle is elevated the pawl engages with the ratchet teeth and rotates the pinion, thus moving the frame upward.

Bearings a^9 , integral with the upper edge of the ends of the frame, support a rod a^{19} , and upon the rod are journaled the strikers a^{20} , the strikers corresponding in number to the keys, and being of the shape shown in Figs. 2 and 7 comprising a horizontal portion a^{21} , and a vertical portion at each end of the horizontal portion, one of said vertical portions a^{22} , being provided with an elastic striker head a^{23} , for engaging the keys, and the other vertical portion a^{24} , being engaged by a spring a^{25} , connected to an arm a^{26} secured to the base of the frame, and normally maintaining the striker out of engagement with the keys.

Each of the strikers a^{20} is provided with an armature a^{27} , and beneath the armature is arranged the fixed core a^{28} , of an electro-magnet a^{29} supported upon the base, the electro-magnets corresponding in number to the strikers. It will be evident that when a current is passed through the electro-magnet, the core will be magnetized and will attract the armature of the striker, thus bringing the striker head into contact with the key, depressing the same. By adjusting the frame with respect to the bracket and consequently with respect to the keys, the force of the blow given by the striker may be varied as desired.

In Figs. 3 to 6 inclusive, I have shown my improved circuit controlling mechanism, the said mechanism comprising series of switches, adapted to complete the circuit between the individual electro-magnets and a battery D , whereby to depress the strikers, the switches being operated by mechanism hereafter described. The switch mechanism is arranged upon a block b^0 , the block being provided with a plurality of transverse openings b , and having at one end a grip b' , for convenience in manipulating the same. Longitudinal ribs b^2, b^3 , are arranged upon the upper face of the block,

the ribs being spaced apart from each other and having upon their upper edges insulating strips b^1 . Bars b^5 of conducting material are inserted in the substance of the insulating strips at spaced intervals. The end bars of the strips at one end of the block are connected by a conductor c and the end bars of the strips at the other end of the block are connected by the conductor c' having interposed in the length thereof a battery B . A plate b^6 is supported above the block b^9 by brackets b^{20} , the edges of the plate being directly above the conducting bars, and provided at intervals with spaced pairs of binding posts b^7 . A conductor c^a , leads from one member of each pair to the other, a single electro-magnet being interposed in the conductor. Below the plate b^6 , and in the same vertical plane with the longitudinal center thereof, is supported a rod b^9 , to which are hinged switch plates b^{11} , the said switch plates being arranged in opposite series, and the inner ends of the members of one series abutting against the inner ends of the members of the opposite series. Upon the lower face of each switch plate at the outer end thereof, is a plate b^{21} insulated from said switch plate. The switch plates b^{11} normally rest upon the conducting bars b^5 , in such position that the plates b^{21} complete the circuit between said bars, that is, one plate b^{21} rests upon two bars covering the gap between the same. Posts b^{12} , b^{13} , are fixed in the vertical openings in the switch plates, the said posts extending above and below the plates and being bent outwardly at a right angle at their lower end. The posts are insulated from the switch plates, and are so arranged that when the outer end of the switch plate is elevated, the upper ends of the posts will contact with the members of a pair of binding posts, while the angular portions will contact with the adjacent conducting bars b^5 , thus interposing in the circuit the electro-magnet connected with the respective pair of binding posts. When the switch plate is elevated, the circuit instead of passing through one conducting bar b^5 and a plate b^{21} to the adjacent conducting bar b^5 will pass from the conducting bar b^5 through the insulated posts and the binding post to the electro-magnet, and pass thence through the other binding post and insulated post to the other conducting bar. Yokes b^{16} are provided for manipulating the switch plates, the said yokes having their body portion projecting through a slot b^2 , and pivotally mounted upon a rod b^{22} supported by one of the brackets b^{20} of the block b^9 . The slots communicate with the perforations b and the lower end of the yoke body is formed into a vane b^{19} , adapted to be engaged by a current of air passing through the perforations whereby to rock the yoke upon its pivot. The arms b^{17} of the yoke project in opposite directions, and are arranged in such

manner that when the yoke is rocked upon its pivot in one direction, one of the arms will lift a switch plate, while, when it is rocked in the opposite direction, the opposite arm will lift the corresponding switch plate of the opposite series. The wires making up the different circuits between the pairs of binding posts of the electro-magnets, are connected into a cable C , before leaving the block, and the switch mechanism is protected and concealed by a cover b^{35} .

In order that both the bass and soprano parts may be played upon the piano or organ at one time, I preferably provide two sets of circuit controlling mechanisms, both of said mechanisms, however, being similar in every respect, half of the strikers being connected with one and the other half with the other.

In operation, when the player blows into one of the perforations b , the upper portion of the yoke body will be rocked toward the player, thus elevating the switch and completing the circuit including the electro-magnet connected therewith, whereby to sound the key engaged by the striker corresponding to the electro-magnet. When, however, suction is created in the perforations, the yoke rocks in the opposite direction and elevates the opposite plate, thereby playing another key. In practice, I prefer to connect the strikers to the switch plates in a manner corresponding to the placing of the reeds in a mouth organ, so that one familiar with the playing of a mouth organ may operate the piano player.

What I claim is:

1. In a piano player and in combination, a plurality of strikers for depressing the individual keys, an electro-magnet for operating each of the strikers, a battery, and means for connecting the battery with a predetermined electro-magnet, comprising a block having a plurality of transverse perforations, a plurality of spaced conducting bars on the block and insulated therefrom, an electrical connection between the end bars at one end of the block, an electrical connection between the end bars at the other end of the block, and including the battery, the terminals of each of said electro-magnets being arranged above adjacent conducting bars, switch plates normally connecting the adjacent conducting bars, means on said plates for completing the circuit between the conducting bars and the adjacent pair of terminals of an electro-magnet when the switch plate is elevated, and means for elevating said plates comprising a yoke having an arm for moving the switch plate, and a vane within one of the transverse perforations, said vane being adapted to be moved by a current of air passing through the perforation.

2. In a piano player and in combination, means for depressing the individual keys, electro-magnets for operating said depressing

means, a battery, and means for connecting the battery with a predetermined electro-magnet, comprising a block having a plurality of perforations, a plurality of spaced conducting bars on the block and insulated therefrom, an electrical connection between the end bars at one end of the block, and an electrical connection between the end bars at the other end of the block, and including a battery, a plate supported above the block and provided with spaced pairs of binding posts, the terminals of each of said electro-magnets being connected with a pair of said binding posts, switch plates normally resting upon and connecting the adjacent conducting bars, means on said plates for completing the circuit between the conducting bars and the adjacent pair of binding posts when the switch plate is elevated, and means extending into the perforations of the block and adapted to be moved by a current of air passing therethrough for operating the switch plates.

3. In a piano player and in combination, a plurality of strikers for depressing the individual keys, an electro-magnet for operating

each of the strikers, a battery, means for connecting the battery with a predetermined electro-magnet, comprising a block having a plurality of transverse perforations, a plurality of spaced conducting bars on the block and insulated therefrom, an electrical connection between the end bars at one end of the block, an electrical connection between the end bars at the other end of the block and including a battery, the terminals of each of said electro-magnets being arranged above adjacent conducting bars, means for completing the circuit between the conducting bars and the adjacent pair of terminals on an electromagnet, comprising a switch plate pivotally mounted on the block, and means engaging the switch plate and having a vane within one of the transverse perforations, said vane being adapted to be moved by a current of air passing through the perforation.

ROBERT MORGAN.
